UNITED STATES PATENT OFFICE.

JOHN R. ROGERS, OF BROOKLYN, NEW YORK, ASSIGNOR TO MERGENTHALER LINOTYPE COMPANY, A CORPORATION OF NEW YORK.

TYPOGRAPHICAL MACHINE.

1,137,024.

Specification of Letters Patent.

Patented Apr. 27, 1915.

Application filed January 13, 1915. Serial No. 1,895.

To all whom it may concern:

Be it known that I, JOHN R. ROGERS, a citizen of the United States, residing at Brooklyn, in the county of Kings and State 5 of New York, have invented certain new and useful Improvements in Typographical Machines, of which the following is a specification, reference being had therein to the accompanying drawing.

- 10 My invention relates to typographical machines, such as linotype machines of the general organization represented in Letters Patent of the United States, No. 436,532, to O. Mergenthaler, wherein circulating matrices are released from a magazine in the order in which their characters are to appear in print and then assembled in line, the composed line transferred to the face of a mold, the mold filled with molten metal to 15 form a slug or linotype against the matrices which produce the type characters thereon, and the matrices thereafter returned through distributing mechanism to the magazine from which they started.
- 20 More particularly, it relates to the distributing mechanism and specifically to the formation of the conveyer screws which move the matrices along the ribbed or permutated distributor bar.
- 25 In the ordinary construction of linotype machines, the distributor rail or bar is constructed with a series of distributing combinations of equal extent, to release the correspondingly toothed matrices at certain 30 definite points, and the threaded conveying screws are correspondingly formed with a number of convolutions equal to that of the combinations on the bars. In other words, the pitch of the screw is equal to the length 35 of the combinations. As a result of this arrangement, and as the machines have been developed, certain disadvantages have arisen, which it is the purpose of my invention to overcome. Thus, where much thicker 40 matrices are employed, it has been found necessary to provide means to convey them to alternate convolutions in order to prevent their too close proximity and interference when released. Again, when it is wished 45 to increase the speed of distribution, it has been necessary to increase the rotational rate of the screws, and sometimes to an un-

desirable extent. My improved construction and arrangement entirely obviate these requirements.

Generally speaking, I propose to vary the pitch of the screws relatively to the rail, so that the number of convolutions thereof is less than that of the distributing combinations on the rail. By this arrangement the 55 matrices are transported along the rail at a greater distance from each other, and more time is permitted them to drop, thus obviating the danger of interference, and as a consequence dispensing with the necessity 60 of feeding the matrices to alternate convolutions. In addition, a high speed of distribution is secured without the necessity for increasing the rotational rate of the screws. Again, and due to the increased 65 angularity and the form of the groove, the latter closely embraces the projecting ears of the traveling matrices, and thus prevents them from swinging or tilting as they travel along the bar; and further, the increased 70 width of the thread on the lower screw enables it to contact with the upper ears of the falling matrices, and to serve as a guide whereby they are properly positioned in entering the channel entrance.

80 In the accompanying drawing, I have shown my invention only in preferred form and by way of example, and as applied to the ordinary style of linotype machine. However, many changes and variations may 85 be made therein, and in its mode of application, which will still be comprised within its spirit. Further, it may be adapted to other forms of typographical machines, such as typesetters, typecasters and the like, which 90 handle type or dies, instead of matrices. Generally speaking, I desire it to be understood that I do not limit myself to my specific form or embodiment, except in so far 95 as such limitations are specified in the claims.

In the accompanying drawing. Figure 1 is a rear view, partly broken away, of a portion of the distributing mechanism of a linotype machine, having my invention applied thereto; and Fig. 2 is a transverse vertical section thereof.

The matrices X are as usual delivered one by one to the distributor bar or rail A and

conveying screws B by the reciprocating finger C, and as they pass along the bar they are released therefrom at the proper points and pass downwardly into the channel entrance D, and thence to the magazine (not shown). It will be noted that three screws B are employed, two being arranged to engage the upper ears of the matrices at opposite sides thereof, and the third to engage the lower ears projecting from one side thereof. So far as described, the parts are or may be of the usual form and mode of operation, which, except as hereinafter specified, constitute no part of my present invention.

As previously stated, in the ordinary construction of linotype machine, the number of distributing combinations A¹ on the bar A is the same as the number of convolutions on the screws B. In the present instance, I construct the screws B with a smaller number of convolutions, in the specific example shown, only half as many as the number of combinations upon the bar. It will be noted that the pitch of the groove B¹ upon each screw is twice that formerly employed, say one-half inch, whereas the length of the combination A¹ on the bar remains the same, say one-quarter inch. The relation of the extent of the combinations to the pitch of the screw is graphically indicated by the diagrams a and b respectively in Fig. 1. It will be noted that this arrangement materially increases both the distance between successive matrices as well as the speed of distribution, with the results and advantages previously indicated. It will also be observed that the increased angularity and the form of the groove B¹ brings its sides into more intimate relation to the ears X¹ of the matrices, in fact so as to embrace them closely, with the attendant advantage that the matrices are thereby prevented from swinging or tilting throughout their travel along the bar. It will also be seen that the width of the thread B² is materially increased, in such manner that the thread on the lower screw now serves to contact with the upper ears of the falling matrices (Fig. 2), and so as to guide or tilt the latter into proper position to enter the magazine entrance D.

As previously stated, I have shown my invention only in preferred form and by way of example, and as applied to a specific kind of machine, but obviously many modifications and alterations therein, and in its mode of adaptation, will suggest themselves to those skilled in the art, without departure from its scope.

Having thus described my invention, its construction and mode of operation, what I claim and desire to secure by Letters Patent of the United States, is as follows:

1. Distributing mechanism for typographical machines comprising a distributor bar formed with a series of distributing-combinations, and rotating screws for conveying the type or matrices along the bar, the number of convolutions of each of said screws being less than that of the distributing-combinations, for the purpose described.

2. Distributing mechanism for typographical machines comprising a distributor bar formed with a series of distributing-combinations to release the type or matrices at different points in its length, and rotating screws for conveying the type or matrices along the bar, the pitch of said screws being greater than the distance between adjacent releasing-points on the bar, for the purpose described.

3. Distributing mechanism for typographical machines comprising a conveying screw having its thread of greater width throughout than that of its groove, for the purpose described.

4. Distributing mechanism for typographical machines comprising a distributor bar along which the type or matrices travel, and a conveying screw having a spiral groove wherein the projecting ears of the type or matrices engage, the said groove having its opposite walls arranged in such proximity throughout as to embrace closely the projecting ears of the type or matrices; whereby the latter are prevented from swinging or tilting throughout their travel along the bar.

5. Distributing mechanism for typographical machines comprising a distributor bar along which the type or matrices travel, and a conveying screw having a spiral groove wherein the projecting ears of the type or matrices engage, the said groove being of such form and angularity throughout as to embrace closely the projecting ears of the type or matrices; whereby the latter are prevented from swinging or tilting throughout their travel along the bar.

6. Distributing mechanism for typographical machines comprising a distributor bar along which the type or matrices travel, and three conveying screws for carrying them therealong, two of said screws being arranged to engage the upper ears of the type or matrices projecting from their opposite edges, and the third screw arranged to engage the lower ears projecting from one of their edges, the spiral groove of each of said screws being of such width as to embrace closely the respective ears of the type or matrices; whereby the latter are prevented from tilting or swinging as they are carried along the bar.

7. Distributing mechanism for typographical machines comprising a distrib-

uter bar, and a conveying screw to engage the lower projecting ears of the type or matrices, the said screw having its thread of such width as to contact with the upper 5 ears of the type or matrices as they drop from the bar and thus guide them thereby.

In testimony whereof, I have affixed my signature in presence of two witnesses.
JOHN R. ROGERS.
